UNITED STATES PATENT OFFICE.

CHARLES VILLENEUVE, OF BOISE CITY, IDAHO TERRITORY.

HORSE-POWER.

SPECIFICATION forming part of Letters Patent No. 333,702, dated January 5, 1886.

Application filed November 4, 1885. Serial No. 181,850. (No model.)

To all whom it may concern:

Be it known that I, CHARLES VILLENEUVE, a citizen of the United States, residing at Boise City, in the county of Ada, Idaho Territory, 5 have invented a new and useful Improvement in Horse-Powers, of which the following is a specification, reference being had to the accompanying drawings.

My invention has relation to improvements 10 in horse powers; and the novelty consists in the peculiar construction and combination of parts, substantially as hereinafter fully set forth, and specifically pointed out in the claims.

My invention has for its object to provide a 15 horse-power of that class known to the art in which a belt is employed to communicate motion from the master-wheel to the apparatus or machinery to be operated; to provide means which shall be simple, strong, and durable in 20 construction and thoroughly effective in operation; which can be very readily and expeditiously taken apart for transportation and set up or put together again for operation; which shall be very light in construction and 25 readily repaired when the parts shall have become broken, and which can be manufactured at a minimum of cost.

In the accompanying drawings, Figure 1 is 30 a perspective view of a horse-power embodying my invention. Fig. 2 is a vertical sectional view on the line $x-x$ of Fig. 1. Fig. 3 is a detached view of the base with the bearing-cap, and Fig. 4 is a detailed sectional view of a portion of the rim of the master-wheel.

Referring to the drawings, in which like letters of reference in the several figures denote corresponding parts, A. designates the base of my improved horse-power, which 40 preferably consists of four supporting-beams, a , having inclined upper faces which meet at a common center, and to which a bearing-plate, a' , is secured.

B designates a cap-piece mounted so as to 45 rotate on the plate a' and on a shaft or pin, b' , secured in the base A, the said cap-piece having a series of sockets, b , cut or formed around its periphery for the reception of the inner ends of the radial arms of the master-wheel C. The cap B has a protecting-plate, c , and is held in place on the shaft b' by a nut, c' , or by any other suitable means. The master-

wheel C comprises an outer rim, D, a series of radial arms, E, and an inner supporting track or wheel, F, arranged over the base A 55 and bearing on rollers f , mounted in brackets f' , which are secured to the beams a of said base. The radial arms E of the master-wheel have tenons e at their ends, the inner ends of which fit in the socket b of the cap B and the 60 outer ends in mortises in the outer rim, D. The outer rim, D, is made of a series of segmental bars, D' , a number of protecting-plates, D^2 , which bear on the lower surface of the bars D' and lap over the joints between the 65 same, and a number of strengthening-plates, D^3 , fitted over the joints between the bars D' and the plates D^2 on the upper and lower surfaces, respectively. The plates D^2 project a slight distance beyond the vertical face of the 70 bars D' , and serve to retain the belt G thereon; or the bars may be made slightly concave, and the plates D^2 D^3 are bolted to the bars so as to permit their ready removal for the purpose of taking the wheel apart for transportation. The supporting-track F is also made 75 in sections F' , which are bolted or otherwise secured to plates F^2 F^3 . The radial arms or spokes of the master-wheel pass between the sections F' , which are separated for this purpose, and the circumferential plates F^2 F^3 are 80 arranged on the upper and lower faces of the sections F' . The plates F^2 are left solid and rest on the friction-rollers f of the base, while the plates F^3 are slotted or cut away on their 85 inner periphery, as at g , to permit the radial arms to move up and down therein for a purpose presently described.

G' designates the draft-bar, secured to the master-wheel so as to permit the draft-animal 90 to walk inside of the wheel between two of the spokes or arms thereof; and, if desired, a number of these bars may be provided, according to the power required.

To take the wheel apart for the purpose of 95 transporting the same, the nut c' is removed from the bolt or shaft of the base and the cap-cover plate c removed, when the outer rim, D, drops down to the ground or on supports provided therefor, the radial arms or spokes 100 E working in the slots g of the upper plate of the track or wheel F. The plates D^3 D^2 of the rim D are now removed, the plate F^3 of the supporting-wheel F removed, and the arms or

spokes E disconnected from the wheels, the sections of which are then packed for transportation.

The master-wheel can be readily and quickly 5 taken apart for transportation and very conveniently put together, and the base A and its attached cap are very readily transported.

Various slight changes in the form and proportion of parts can be made without de- 10 parting from the principle of my invention.

Having thus fully described my invention, what I claim as new, and desire to secure by Letters Patent, is—

1. In a horse-power, the combination of a 15 base, a cap rotatively mounted thereon, and a sectional master-wheel having its spokes or arms fitted in the cap, substantially as de- scribed.

2. In a horse-power, the combination of a 20 base, a cap rotatively mounted thereon, a master-wheel having its arms fitted in the cap, a supporting wheel or track secured to the master-wheel, and friction-rollers on which the supporting-wheel bears, substantially as de- 25 scribed.

3. In a horse-power, the combination of a

base, a cap mounted thereon, a sectional master-wheel having its arms fitted in the cap, a sectional track secured to the master-wheel, and a series of rollers mounted on the base 30 and bearing against the track, substantially as described.

4. In a horse-power and in combination with the base thereof, a master-wheel comprising a series of segmental bars detachably fitted together and removable protecting and brace plates secured over the joints between said bars, substantially as described. 35

5. In a horse-power, the combination, with a base and a master-wheel mounted thereon, 40 of a track secured to the master-wheel and comprising segmental bars and circumferential securing-plates, and a series of supporting-rollers, substantially as described.

In testimony that I claim the foregoing as 45 my own I have hereto affixed my signature in presence of two witnesses.

CHARLES VILLENEUVE.
